DESCRIPTION

FIG. 1 is a bottom plan view of a pacifier holder, showing my new design;

FIG. 2 is a right side elevational view thereof, the left side elevational view being a mirror image; and.

FIG. 3 is a top plan view thereof.

The cross-line pattern on the surface of the design which is partially shown for ease of illustration represents a conventional fabric. The broken line showing on FIG. 2 represents top-stitching.
